UNITED STATES PATENT OFFICE

MARVIN L. CHAPPELL, OF LOS ANGELES, CALIFORNIA, ASSIGNOR TO STANDARD OIL COMPANY OF CALIFORNIA, OF SAN FRANCISCO, CALIFORNIA, A CORPORATION OF DELAWARE

PROCESS OF PRODUCING NAPHTHA FROM HYDROCARBON OILS

Application filed December 1, 1926. Serial No. 151,876.

This invention relates to a process of treating hydrocarbon oil to produce low boiling point oil such as naphtha or gasoline.

An object of the present invention is to provide a process of treating hydrocarbon oil with metallic halide which will enable the production of a larger percentage of naphtha from the hydrocarbon oil than can be produced in accordance with the usual procedures.

More particularly an object of the present invention is to provide a process for treating hydrocarbon oil with metallic halide in which the fresh metallic halide is brought first into contact with the hydrocarbon oil or vapors thereof at a comparatively low temperature and is thereafter contacted at an increased or higher temperature with a hydrocarbon oil. Preferably this is accomplished by feeding the metallic halide into a reflux tower connected with a reaction chamber so that the metallic halide first comes into contact with the vapors and condensate products within said tower and therefrom passes into the reaction chamber. In this way, the first reaction between the metallic halide and hydrocarbon oil is at a comparatively low temperature while the second reaction in the reaction chamber is at an increased temperature. Therefore, the fresh metallic halide has an opportunity for reacting upon hydrocarbon oil in the absence of any metallic halide sludge produced from the high temperature treatment.

A further object of the present invention is to provide a method for producing naphtha from hydrocarbon oil in which the naphtha is produced partially by a metallic halide reaction and partially by a thermal cracking reaction with such passage of materials from one reaction to the other as is conductive to the most efficient production of the low boiling point oil or naphtha. In accordance with the present process, all of the hydrocarbon oil charged into the cracking apparatus is first subjected to an action with metallic halide with the result that said oil is both freed from sulfur content and polymerized to eliminate unsaturated materials. At the same time, the condensed high boiling point

material derived from the cracking reaction is fed back into an aluminum chloride reaction chamber where this material which is of unsaturated nature, is polymerized for the production of further gasoline in accordance with the metallic halide reaction or else for repassage to the cracking reaction chamber.

The present invention, therefore, results in the production of naphtha from petroleum oils or hydrocarbon which has a substantially lower sulfur content than the naphthas normally produced by a cracking reaction and all fractions of the hydrocarbon or petroleum oil are repeatedly acted upon until the entire feed of petroleum oil may be converted into either naphtha or coke.

Various further objects and advantages of the present invention will be apparent from a description of a preferred form or example of a process embodying the invention. For this purpose, reference is made to the accompanying drawing in which there is illustrated a form of apparatus in which the process of the present invention may be performed.

The drawing represents a diagrammatic view of the apparatus in which the parts are mainly in vertical section.

Referring to the drawing, the preferred continuous process is performed by passing the fresh oil to be treated from a line 2 by means of a pump 6 through a preheater 3 to a line 4, and hence through a heating coil 5 into a reaction chamber 7. The process will be described referring particularly to the treatment with aluminum chloride as the metallic halide, but it is to be understood, however, that aluminum chloride is to be regarded merely as an example of a metallic halide. The preheater 3, as later brought out, preferably is positioned within a dephlegmator or reflux tower 8 for the reaction chamber 7, thus operating as a control over the discharge temperature of vapors from said tower. The heating coil 5 is preferably of the once-through type and is located within any suitable heating means, such as the furnace 9 having the burner 10. The reaction chamber 7 may be of any suitable type for commingling aluminum chloride and hydrocarbon

oil at a reacting temperature, being indicated as preferably a horizontal cylindrical tank having an agitator 11. Said reaction chamber 7 is preferably provided with a 5 valved residual withdrawal line 12 and is also preferably mounted on a furnace 13 provided with a burner or other suitable heating means 14.

As the hydrocarbon oil to be processed, any 10 hydrocarbon oil, either a petroleum oil, shale oil, or oil derived from coal or similar products, may be employed. As an example of a preferred oil, a petroleum oil or a gas oil fraction thereof having a gravity between 15 20° and 29° Baumé may be employed.

Preferably the hydrocarbon oil is heated in the heating coil 5 to substantially the reaction temperature desired to be maintained in reaction chamber 7. Said temperature will depend largely upon the character 20 of oil supplied to the system and the percentage of aluminum chloride provided for reacting therewith and also upon the pressure employed and the extent of reaction desired 25 in said chamber. Generally the temperature will range between 500° and 600° F., although temperature from 400° to 700° F. may at times be employed. Particularly with the 30 higher temperatures, a certain amount of the hydrocarbon oil may be thermally decomposed or cracked and vaporized from the system, in which case however said decomposed oil will be reacted upon by the aluminum chloride in dephlegmator 8. It is an 35 advantage also in the process to operate at comparatively high temperatures, such as 600° F., or higher, when the aluminum chloride conversion process is carried out, together with the subsequent thermal cracking 40 operation as such higher temperatures operate to insure a more efficient removal of the sulfur content of the oil.

Within reaction chamber 7 and upon the vapor separating apparatus, therefore, a 45 pressure is preferably employed. Pressure, however, is not essential to this portion of the reaction and, in fact, below atmospheric pressure may be employed. However, it is generally found that the efficiency is increased where the pressure upon the reaction 50 chamber 7 is maintained above atmospheric, for example, from 15 to 50 pounds gage.

Additional heat may be supplied to the reaction chamber 7, if desired, in order to maintain the reaction temperature, although 55 this is not generally necessary. Within the reaction chamber 7, the hydrocarbon oil reacts with metallic halide or metallic halide fluid sludge or tar from dephlegmator or 60 reflux tower 8. The reaction in chamber 7 is preferably regulated so that all of the metallic halide sludge fed thereto is reduced to a solid mass or coke while at the same time 65 all of the hydrocarbon oil not decomposed into coke is vaporized from the chamber, to-

gether with the produced naphtha. The vapors from reaction chamber 7 pass out vapor line 15 and enter the dephlegmator or reflux tower 8 near the bottom thereof but at a point slightly above the bottom. Within 70 the reflux tower or dephlegmator 8, some vapors are separated so that all of the oil not within the boiling point range of the desired naphtha are condensed and fall to the bottom of the tower. The produced naphtha passes 75 out through line 16 to condenser 17 wherein it is condensed and hence passed to the naphtha or gasoline tank 18 which is indicated as 80 preferably provided with a valved vent line 19.

In the dephlegmator or reflux tower 8, the metallic halide is added either continuously or intermittently. Said metallic halide is added from charger 20 which is indicated as 85 provided with a hopper 21 for use when the material is added in solid form and with a line 22 through which liquid metallic halide may be added, for example, metallic halide admixed with sufficient hydrocarbon oil to 90 make the same liquid.

The fresh metallic halide first comes into contact with hydrocarbon oil in the dephlegmator or reflux tower 8 wherein it reacts upon the hydrocarbon oil for the further 95 production of naphtha and also for the polymerization of any cracked stock which might have been formed in reaction tower 7. It is understood that the metallic halide in its descent to the reflux tower 8 progressively comes into contact with the condensed oil 100 on each of the different compartments of the dephlegmator and is finally collected in the lower end of the reflux tower and hence passed through line 23 to reaction chamber 7. Due to the cooling action of the feed oil and heat exchanger or planer 3, the temperature within the reflux tower 8 is lower than 105 the temperature of reaction chamber 7. For example, when operating at 15 pounds pressure, the discharge temperature at the top of the dephlegmator is ordinarily around 330° F., while the lower end of the dephlegmator will operate generally about 100° F. lower than the temperature of the oil or admixture within reaction chamber 7.

In the bottom of dephlegmator or reflux tower 8 both metallic halide sludge and condensed high boiling point oils are collected. These materials stratify so that the hydrocarbon oil occupies the upper layer. The reflux tower 8 is indicated as preferably provided with an automatic control for a valve 24 on the line 23 which conducts the metallic halide to reaction chamber 7, said control including the float 25. The float 25 or other suitable liquid level indicating and regulating device adapted to float on the tarry reaction sludge, may be connected in any suitable manner with the valve 24 so as to open said valve whenever the sludge accumulates. 130

The oil present above the sludge layer is withdrawn from the tower 8 by line 26.

The high boiling point hydrocarbon oil condensed within the reflux tower 8 may be withdrawn therefrom to a receiver for processing in any desired manner or may be passed again to reaction chamber 7 but preferably is passed to a thermal cracking apparatus of any desired or suitable type. It is understood that the feature of adding the metallic halide to a reflux tower of the reaction chamber 7 is not necessarily dependent upon the simultaneous passage of the refluxed oil to a cracking process. Preferably, however, said condensed oil is continuously passed from reflux tower 8 through line 26 wherein it is raised in pressure by pump 27 and passed once through a heating coil 28. Within the heating coil 28, said oil is raised to a cracking temperature such, for example, as around 750° to 850° F., the heating coil 28 being indicated as heated by suitable means such, for example, as the furnace 29 having the burner 30.

From the heating coil 28, the hydrocarbon oil is passed to a reaction chamber 31 wherein the cracking reaction is permitted to complete itself and the produced naphtha is permitted to vaporize. In said reaction chamber 31, the oil is reduced to naphtha and a tarry residue which may be continuously withdrawn through line 32 or the oil may be reduced to naphtha and coke. The vapors from reaction chamber 31 are passed through vapor line 33 to a reflux tower or dephlegmator 34. Said reflux tower 34 is indicated as provided with a planer 35 having water inlet and outlet lines 36 and 37, respectively, by means of which the temperature of the vapors discharged from the tower may be regulated to condense therefrom all fractions which have boiling points without the range of the desired naphtha or gasoline. Said naphtha or gasoline passes from the reflux tower 34 through line 38 to a condenser 39 and hence into a storage vessel 40 having a valved vent line 41. The pressure imposed upon the oil during the before-described cracking reaction is generally from 80 pounds to 300 pounds per square inch although higher pressures may be employed. It is understood that the particular details of the cracking reaction described are not essential to the present process.

The condensed high boiling point oils in dephlegmator 34 are preferably passed through a line 42 into the metallic halide reaction chamber 7. In said reaction chamber 7, said high boiling point oils, a considerable portion of which have been rendered unsaturated through the cracking reaction, will be readily acted upon by the metallic halide and converted either into naphtha or saturated high boiling point oils.

By the process thus described, both me-

tallic halide conversion and thermal conversion are applied to a hydrocarbon oil under such conditions as are found to produce or result in the maximum conversion of said oil to naphtha with the minimum loss of hydrocarbon oil, it being found that the two processes inter-related in the before-described manner coordinate together most efficiently in the production of naphtha. All of the hydrocarbon oil subjected to thermal decomposition is first subjected to contact or reaction with a metallic halide thereby removing unsaturated materials and sulfur bearing constituents therefrom which are detrimental in the thermal cracking reaction and all of the high boiling point oil containing unsaturated materials derived from the thermal cracking reaction is recirculated to the zone where the hydrocarbon oil is undergoing reaction with metallic halide, whereby said hydrocarbon oil is rendered saturated and in condition for better processing for the production of further naphtha.

While the process herein described is well adapted to carry out the objects of the present invention, it is understood that various modifications and changes may be made without departing from the invention and the invention includes all such modifications and changes as come within the scope of the appended claims.

I claim:

1. A process of treating hydrocarbon oil with metallic halide which comprises contacting fresh hydrocarbon oil and metallic halide in a reaction zone under conditions to reduce all of the tarry residue containing metallic halide to a solid mass or coke and at the same time vaporize all of the hydrocarbon oil not decomposed into coke, passing the vapors to a reflux zone, therein introducing the fresh metallic halide into the system, and passing the metallic halide and metallic halide reaction products from said reflux zone to said reaction zone.

2. A process of treating hydrocarbon oil with metallic halide which comprises contacting fresh hydrocarbon oil and metallic halide in a reaction zone under conditions to reduce all of the tarry residue containing metallic halide to a solid mass or coke and at the same time vaporize all of the hydrocarbon oil not decomposed into coke, passing the vapors to a reflux zone, therein introducing the fresh metallic halide into the system, passing the metallic halide and metallic halide reaction products from said reflux zone to said reaction zone, withdrawing the condensed high boiling point oils in said reflux zone, and subjecting said condensed oils to the requisite temperature and pressure to thermally decompose said oils without a halide catalyst into lower boiling point oils.

3. A continuous process of treating hydrocarbon oil which comprises continuously sup-

plying fresh hydrocarbon feed oil to a reaction zone, continuously passing vapors from said reaction zone to a reflux zone, supplying metallic halide to said reflux zone, separating metallic halide from condensed high boiling oils from said reflux zone, passing metallic halide from such reflux zone to said reaction zone, withdrawing the condensed high boiling point oils from said reflux zone, and subjecting the same to the requisite temperature and pressure to thermally decompose the same without a halide catalyst into lower boiling point oils.

4. A process of treating petroleum oils with metallic halide comprising maintaining a body of petroleum oil and metallic halide undergoing reaction in a reaction zone, evolving vapors from said mixture, passing the vapors to a reflux zone contacting metallic halide with said vapors within said zone at a progressively increasing temperature, separately vaporizing oils condensed within said reflux zone, passing said vapors to a second reflux zone and returning oil condensed within said second reflux zone to the first reflux zone.

5. A process of treating petroleum oils with metallic halide comprising maintaining a body of petroleum oil and metallic halide undergoing reaction in a reaction zone, evolving vapors from said mixture, passing the vapors to a reflux zone, contacting metallic halide with said vapors within said zone at a progressively increasing temperature, separately vaporizing oils condensed within said reflux zone, passing said vapors to a second reflux zone and returning oil condensed within said second reflux zone to the reaction zone.

6. A process of the character described comprising contacting metallic halide with vapors from an oil-metallic halide reaction zone at progressively increasing temperatures in a reflux zone, revaporizing oil condensed within said reflux zone under cracking temperature and pressure conditions, passing such vapors through a second reflux zone and returning oil condensed within said second reflux zone to the first reflux zone.

7. In a process of treating hydrocarbon oils with metallic halide, the steps of contacting feed oil with partially spent metallic halide in a reaction zone at reaction temperatures, passing oil vapors evolved by such contact into a reflux zone, contacting said oil vapors with fresh metallic halide in such reflux zone, discharging treated oil vapors from said reflux zone, separately discharging condensed and partially treated oil from said reflux zone, and separately vaporizing and dephlegmating said partially treated oil.

Signed at San Francisco, California, this 19th day of November, 1926.
